Beehler Vending Machines, Inc., a corpora-
tion of New York

Application September 7, 1929
Serial No. 391,006

5 Claims. (Cl. 312—97)

This invention relates to the dispensing mechanism of a coin controlled vending machine. The coin controlled mechanism which has been utilized in carrying out this invention is the same as that disclosed and claimed in my prior co-pending application which became Patent No. 1,734,739, dated November 5, 1929, for coin controlled mechanism. Some of the features of the dispensing mechanism employed in carrying out the invention are substantially similar to some of the features disclosed and claimed in my Patent No. 1,722,230, dated July 23, 1929, for Vending machine. In carrying out the invention the coin controlled mechanism constitutes a step-by-step operating mechanism such as is required for operating the dispensing mechanism of this invention. So far as this invention is concerned, any other suitable coin controlled mechanism, or other suitable step-by-step operating mechanism without coin control, could be utilized for that purpose. Accordingly, features of construction relating more particularly to coin controlled operation have been omitted from the drawings, although a few of these appear incidentally, and complete information may be obtained from my above noted Patent No. 1,734,739.

One of the objects of the invention is to provide a vending machine having a capacity for containing a large number of relatively small packages or articles which are to be dispensed or vended one at a time at each operation of the machine. Another object is to provide for the convenient and speedy filling or loading of the machine with articles or packages when its magazine requires replenishing. Another object is to provide for the automatic vending of frail articles or packages in good condition and undamaged in the vending operation, that is, without having their wrappers disarranged or torn, or the contents of the wrappers crushed or broken, such as chocolate bars of candy in paper or tinfoil wrappers, as well as many other articles and packages which require careful handling in order to prevent damage thereto. Another object is to provide a vending machine in which the above noted coin controlled mechanism may be utilized for operating the dispensing mechanism of the machine. Other objects are to provide a vending machine of a construction which is easy to manufacture, effective in operation, simple, strong, durable, compact, dependable, convenient and reliable. Other objects and advantages of the invention will hereinafter appear.

In carrying out the invention the dispensing mechanism is so constructed and operated that

single articles will be delivered one by one alternately from a pair of endless traveling stock-carrying carrier chains, which form delivery chains, at each operation of the machine. These endless chains have front and rear vertical runs both of which are to be loaded with articles or packages to be dispensed by delivery at the bottoms of the runs in the traveling step-by-step movement of these chains. In order to facilitate the loading of the rear runs of these carrier chains, these chains are carried by a swinging frame which is pivoted at its lower end to be tilted or swung forwardly and downwardly from the front of the vending machine casing so that thereby the rear runs of these chains are then exposed and freely accessible from above. Also for affording further convenience and celerity in loading the carrier chains, the dispensing mechanism includes a manually releasable clutch device by which the carrier chains may be disconnected from their drive shaft, which is operated by and has a positive connection to the coin controlled operating mechanism, so that when these carrier chains are thus disconnected they will then be free to be moved while they are being loaded with articles or packages to be delivered by these chains in the dispensing operation. The invention further includes various features of construction and combinations of parts, as will appear from the following description.

The embodiment of the invention which is illustrated in the accompanying drawings will now be particularly described and thereafter the invention will be pointed out in claims, reference now being had to these drawings, in which:

Fig. 1 is a front elevation of the interior parts of a vending machine embodying the invention, with the machine casing in vertical section just at the rear of the front door, the normally exposed front frame plate of the coin controlled mechanism also appearing in elevation, together with the operating handle of the machine.

Fig. 2 is in part a side elevation and in part a vertical section substantially on the zig-zag line 2—2 of Fig. 1.

Fig. 3 is a greatly enlarged partial vertical section substantially on the zig-zag line 3—3 of Fig. 2.

Fig. 4 is a side elevation with parts broken out showing the chain-carrying frame as swung outward and downward to the position for loading the rear runs of the carrier chains.

Fig. 5 is a considerably enlarged transverse horizontal section of the swinging chain-carrying

frame alone, the section being taken on the line 5—5 of Fig. 2.

Fig. 6 is an enlarged front view in vertical section taken for the most part substantially on 5 the slightly zig-zag line 6—6 of Fig. 2, with portions at the top and adjacent thereto omitted, as indicated by the broken transverse lines.

Fig. 7 is a similar but further enlarged partial vertical section taken substantially on the short 10 zig-zag line 7—7 of Fig. 2, showing in section the releasable clutch device and gearing connection which appear at the right side in Figs. 1 and 6.

Fig. 8 is an enlarged side elevation of one of the carrier chain links per se, with this link in the 15 position it would have in the front run of a carrier chain when viewed from the right side of the machine, as in Figs. 2 and 10.

Fig. 9 is a plan view of the same link.

Fig. 10 is a considerably enlarged partial vertical section taken on the zig-zag line 10—10 of 20 Fig. 6, Figs. 7 to 10 inclusive being drawn to substantially the same scale, which is further enlarged over Fig. 6, and which is about the full size of the machine.

25 In the embodiment of the invention illustrated in the accompanying drawings and now to be particularly described, the operating mechanisms of the machine, comprising the dispensing mechanism and the coin controlled mechanism, are contained within a rectangular casing box which may be formed of suitable sheet metal such as steel by means of ordinary stamping and welding operations, this casing box being of greater width than depth from front to rear, and being of 30 greater height than width. This casing box has a back 1, sides 2 and 3, a bottom 4, and a lower marginal front wall portion 5, all of which may be formed from one piece of sheet metal if so desired. A pair of inner mechanism-supporting 35 casing frame walls 6 and 7 are spaced slightly inward respectively from the outer side walls 2 and 3 and may be rigidly but removably secured in place to the rear casing wall 1 and also if desired to its side walls 2 and 3, by any suitable convenient means (not shown). A forwardly opening 40 transversely elongated bent or curved delivery chute is provided between the lower end portions of these frame walls 6 and 7, this chute having a floor wall 8 and an upper wall 9. Since the 45 lower portion of this sheet metal framework supports the coin controlled mechanism, it is stiffened and strengthened by means of three transverse rods 10, and also by means of a bent brace rod 11 disposed in a vertical plane.

50 A removable front door 12 is provided which is extended rearwardly over the top of the casing to form a cover 13. This front door 12 may be flanged into the front of the casing body, as is shown at the top in Fig. 1 for its cover portion 13, and this cover portion 13 is flanged downwardly at the rear at the outside of the back wall 1 so as thereby to have retaining engagement therewith, as shown in Fig. 2. The lower portion of this 55 removable front door 12 is cut out around so as to expose the central portion of a front frame plate 14 of the coin controlled mechanism, as indicated in Figs. 2 and 4 and as shown more clearly in Fig. 10, this door terminating at its lower end at the delivery chute and being shown as flanged inward beneath the forward edge portion of its upper wall 9. This door 12 when opened gives free access to the inside of the casing box from the front and is to be secured in its closed condition by means of a suitable lock (not shown). An 60 inner main frame plate 15 of the coin controlled

mechanism, which is provided with various projections and bosses, is spaced rearwardly from the outer frame plate 14 which is secured thereto by means of screws 16 (Fig. 1). By means of a number of lugs and screws, some of which appear in the drawings, the main frame plate 15 is removably secured in place in the casing, to the left hand frame wall 7 and to the lower margin of the upper wall 9 of the delivery chute.

65 A one-piece carrier frame of inverted U shape comprises side plates 17 and 18 which are integrally connected together at their upper ends by a top plate 19. At suitable distances from their upper and lower ends the side plates 17 and 18 of the carrier frame are tied together and braced by means of a pair of similar flat spacing bars 20 the reduced ends of which may be riveted through the side plates 17 and 18, as shown in 70 Fig. 4 for the upper one of these bars 20. The inside of this carrier frame is divided into four 75 rectangularly arranged similar vertical guide channels by means of intermediate partitions, as shown in the drawings, more particularly in Fig. 5. These carrier frame partitions are formed by means of four sheet metal right-angledly bent L-shaped pieces firmly secured in place, as indicated in Figs. 1 and 5. These partitions, which form guide walls, comprise a double-wall middle partition 21 parallel with and midway between the side plates 17 and 18 with 80 which this partition 21 is substantially co-terminal at its lower end, while at its upper end its front and rear margins are extended up to the top connecting plate 19 and secured thereto (Fig. 1). The other partition is a four-part vertical transverse partition 22 having spaced front and rear walls at the front and rear of the flat tie bars 20 by which the walls of this partition 22 are spaced, and the upper and lower ends of this partition 22 are substantially even or flush with the upper and lower edges of these tie bars 20 (Figs. 1, 6 and 10). A vertically arranged guide plate 23 (Figs. 2 and 10) is spaced inward from and carried by the front door 12 and has its flanged lateral edges secured thereto. Adjacent to but suitably spaced from their lower ends, the side plates 17 and 18 of the carrier frame are fixedly provided with bushings 24 (Figs. 1, 6 and 7) which form bearings.

85 Suitably spaced above the coin controlled mechanism and above the upper end of the above described delivery chute, the inner frame walls 6 and 7 of the casing structure are provided with 90 flanged bearings 25 which are firmly held in place by means of nuts 26 screwed over their tubular stems (Figs. 1, 6 and 7). A hexagonal lower sprocket shaft 27 has reduced cylindrical ends journaled in these bearings 25. Between the right hand frame wall 6 and the right hand plate 17 of the carrier frame, the sprocket shaft 27 has fixed thereon a spur operating gear 28 which is provided with an inwardly extending hub sleeve 29 at the inner end of which there is an abutment washer 30 held in place by a pin 31 through the sprocket shaft 27. The right hand side plate 17 of the carrier frame is pivoted on the gear hub sleeve 29 by means of its bushing 24, and the left hand side plate 18 of this carrier frame, by means of its bushing 24, is similarly pivoted on a flanged sleeve 32 which is similar to the hub sleeve 29 and is similarly held in place on the sprocket shaft 27 by means of an inner washer 33 which is held in place by a pin (not shown) similar to the pin 31.

95 Thus it will be seen that the above described

carrier frame is pivoted at its lower end on the lower sprocket shaft 27 so that thereby this carrier frame together with all parts carried thereby, may be swung or tilted forward and 5 downward as shown in Fig. 4. This swinging carrier frame is normally held at its upright position in the casing by means of a pair of automatically engaging manually releasable gravity latches 34 the hooked outer ends of which engage 10 with headed studs 35 which project from the outer sides of the frame plates 17 and 18 at a suitable distance below the top of the carrier frame. In its tilted position (Fig. 4), in which it is inclined at an angle of about 45°, this carrier 15 frame is supported by a pair of folding links 36 the lower ends of which have slots engaging over headed studs 37 which project outward from the side plates 17 and 18 of the carrier frame at a suitable location shown as below the middle of its 20 length.

The carrier latches 34 and carrier-supporting links 36 (Figs. 1 to 4 inclusive and 6) are pivoted, at the right and left hand sides respectively, on inwardly headed studs 38 which rigidly project 25 inward from the adjacent right and left hand casing frame walls 6 and 7 adjacent to which the pivot studs 38 are provided with spacing washers 39. It may be noted that the right hand carrier plate 17 is spaced inwardly from the frame 30 wall 6 to a sufficient extent for the accommodation of the above described operating gear 28, it being noted that at the left side of the machine the left hand plate 18 of the carrier is spaced inwardly a somewhat lesser distance from the adjacent casing frame plate 7. Except for being 35 slightly shorter the left hand pivot stud 38 is similar to the right hand pivot stud 38 as shown in Fig. 3. What is normally the rear side of the swinging carrier frame when it is in its upright 40 position in the casing, will be fully exposed and freely accessible from above when this frame is swung to its forward position shown in Fig. 4, in which it is supported by the slotted links 36, the lower ends of which are close to the front of 45 the casing, out of the way.

An upper hexagonal sprocket shaft 40 is in general similar to the lower sprocket shaft 27 excepting that this upper sprocket shaft 40 is somewhat shorter and is provided with somewhat longer reduced cylindrical journal ends. This upper sprocket shaft 40 is rotatably carried at its ends by the side plates 17 and 18 of the carrier frame in suitably spaced relation below its top plate 19. At its respective ends this upper sprocket shaft 40 is journaled in a bearing 41 having a flange at the outer side of the adjacent carrier plate and having a flattened screw threaded stem which passes inward through a vertical slot 42 in the carrier plate beyond which this bearing stem projects some little distance to the inside. This inwardly projecting stem of the bearing 41 first receives a washer 43 adjacent to the slotted carrier plate, then it receives a lock washer 44, followed by a nut 45 by which this bearing 41 is securely clamped in place in an adjusted position in the slot 42. An inner washer 46 on the reduced journal end of the sprocket shaft 40 provides an abutment bearing for this shaft against the inner end of the bearing 41. The slots 42, along which the bearings 41 are adjustable, of course provide for adjustably varying the distance or spacing of the upper sprocket shaft 40 from the lower sprocket shaft 27.

In carrying out the invention, the lower sprocket shaft 27 is driven by its operating gear

28 by driving means and in a manner presently to be described. This lower sprocket shaft 27 has fixed thereon small right and left hand driving sprockets 47 and 48, while the upper sprocket shaft 40, which is an idler shaft, has fixed thereon small right and left hand sprockets 49 and 50, which thus are rotatably coupled together by this idler shaft 40 upon which they are fixed. These sprockets are all of the same dimensions with the same number of sprocket teeth and may conveniently be zinc die-castings. For economy of material each of these sprockets has a reduced cylindrical middle portion and is provided with sprocket teeth at its ends only, so that in general the sprocket is of a spool shape, which however has no effect upon its operation, as will presently appear. Each of these sprocket wheels at its toothed ends is in general of a square shape, being provided with four sprocket teeth which are relatively wide and short with flat ends and are formed between and by means of flaring corner notches having narrow curved bottoms and slightly convexly curved rather widely flaring sides, as shown in the drawings, more particularly in Fig. 10 for the lower right hand sprocket 47. Each of these sprocket wheels is provided with a hexagonal axis hole or bore which closely fits and by which it is rotatably coupled to its sprocket shaft. Sliding movement of the sprocket upon its shaft may be prevented in any convenient way, such as by means of a set screw (not shown).

In carrying out the invention, the two lower sprockets 47 and 48 are angularly offset on their operating shaft 27 to an extent of 45° or a one-eighth turn relatively to each other, so that thereby by the corner notches and intervening sprocket teeth on one of these sprocket wheels are disposed in axial planes half way between the axial planes in which the corner notches and sprocket teeth on the other sprocket wheel are disposed. This angular relation of these two sprockets is conveniently obtained and positively assured without necessity of making any adjustment of the sprockets on the sprocket shaft 27 and is thus accomplished simply by correspondingly angularly spacing the hexagonal axial hole or bore through one of these sprockets, to an angular extent of 45° relatively to the hexagonal hole or bore through the other sprocket, so that thereby by the correct angular relation of these two lower sprockets 47 and 48 is then positively determined by the hexagonal sprocket shaft 27 by which these sprockets are coupled together and concomitantly operated.

The two upper sprocket wheels 49 and 50 are similarly angularly offset to an extent of 45° on the sprocket shaft 40 by which they are positively coupled together for concomitant operation. Accordingly, one of these upper sprockets 49 and 50 may be in all respects a duplicate of one of the lower sprockets 47 or 48, and the other upper sprocket may be correspondingly a duplicate of the other lower sprocket. In the particular construction shown in the drawings the right hand upper sprocket 49 is thus a duplicate of the lower right hand sprocket 47 and the left hand upper sprocket 50 is in like manner a duplicate of the left hand lower sprocket 48. However, in view of the fact that the upper sprocket shaft 40 is an idler shaft, it is immaterial to the operation which of these upper sprockets 49 or 50 is at the right hand or at the left. That is to say, the upper sprocket shaft 40 could be turned over end for end together with its sprock-

ets 49 and 50 without thereby affecting the operation, since this upper sprocket shaft 40 is free for angularly adjusting itself as a whole, although in any case it positively rotatably couples together the two upper sprocket wheels 49 and 50, as is desired in carrying out the invention. This above described construction of the sprocket shafts 27 and 40 and of the four-tooth sprockets 47, 48, 49 and 50 facilitates manufacture and also results in the correct angular relation of all of these sprockets relatively to one another.

Right and left hand carrier chains A and B, which also constitute delivery chains, may each be a duplicate of the other per se, as shown in the drawings. The right hand carrier chain A passes beneath the lower right hand sprocket 47 and over the upper right hand sprocket 49 and has normally vertical front and rear parallel runs extending between these sprockets. The left hand carrier chain B similarly passes under the left hand lower sprocket 48 and over the left hand upper sprocket 50 and similarly has normally vertical front and rear parallel runs extending between these left hand sprockets. It will be noted that these carrier chains A and B are not of a full width to fill the lateral space, between the right and left hand frame plates 17 and 18 respectively and the intermediate partition wall 21 (Figs. 1 and 6), since it is unnecessary in carrying out the invention to have these carrier chains of such a greater width. It is to be noted that the vertical transverse partition wall 22 extends in line with the normally vertically aligned sprocket shafts 27 and 40 from just above the lower sprockets 47 and 48 to just below the upper sprockets 49 and 50, and the spaced plates of this partition wall form baffles or guides for the backs of the runs of the carrier chains A and B which prevent the possibility of any interference between the oppositely traveling runs of each of these carrier chains and assure a similar separation and guiding of packages carried respectively by the front and rear runs of the carrier chains, so that thereby there is no possibility of the ends of oppositely moving packages striking against one another.

For carrying out the invention in a practical manner, each of the carrier chains A and B is made up of a series of pivotally connected links each of which comprises a single piece of suitably bent and perforated sheet metal. Each such link comprises an outwardly projecting flat lug 51 which is of sufficient dimensions to provide a shelf upon which an article to be vended may be fully supported. A flat cross bar 52 is turned over at a slightly acute angle from the inner margin of the shelf-providing lug 51. A pair of end arms 53 are turned rearwardly at right angles from the respective ends of the cross bar 52. The ends of each side arm 53 are provided with perforations 54 and 55 the axes of which are in a plane at right angles to the plane of the shelf lug 51. The ends of the arms 53 having therein the perforations 54 project beyond the adjacent free edge of the cross bar 52 and each such projecting portion is bent so as to be offset inwardly a distance equal to the thickness of the metal, so that thereby these projecting ends may overlap at the inner sides of the opposite ends of the side arms 53 on the next adjacent link, in the assembled condition of the chain with the perforations 54 then in alignment with the perforations 55 of the next link in the series. Each link is pivoted to the

next adjacent link by means of a pivot pin 56 which passes through the perforations 54 of one link and the perforations 55 of the other link. Each pivot pin 56 is provided at one end, shown as the left end, (Figs. 1 and 6) with an outer head, its other end being shown as pointed for convenience in effecting assembly, this latter end portion, after assembly, being suitably upset as indicated in Figs. 1 and 6 for thereby holding the pivot pin in place.

It will be noted that in the vertical front and rear runs of one of these carrier chains that the free edge of the cross bar 52 of one of the links abuts against the inner margin of the shelf-forming lug 51 of the next adjacent link, and also that the adjacent angular corner of each link formed between its lug 51 and cross bar 52 abuts against the adjacent outer edges of the projecting portions of the end arms 53 having therein the perforations 54, both of these abutting engagements taking place at points intermediate to the pivot pins 56. By reason of this construction of the chain, it may freely bend in one direction for passing around the sprockets, but it will be rigid against bending in the opposite direction beyond a plane passing through the axes of the pivot pins 56. This prevents the formation of double bends or S bends in the vertical runs of the chain and is therefore of substantial aid in maintaining the package-carrying shelf-providing lugs 51 in a substantially level or horizontal position in these front and rear vertical runs of the carrier chain.

When one of these carrier chains A or B passes around one of the four-tooth sprocket wheels 110 the rearwardly projecting end arms 53 at the sides of the chain pass at the lateral outer sides of the sprocket teeth at the ends of the sprocket, while the pivot pins 56 engage in the corner notches between these sprocket teeth, with the flat outer end of each sprocket tooth just inwardly from the cross bar 52 of a link and with this flat end of the sprocket tooth parallel with a plane passing through the axes of the two adjacent pivot pins 56. Thus it will be seen that the four sprocket teeth engage successively and individually with the successive links in the carrier chain, each sprocket tooth engaging with a single link as the chain passes around the square sprocket wheel, as is shown in the drawings, more particularly in Fig. 10. Therefore, each complete rotation of one of the four-tooth sprocket wheels will reverse the position of four of the carrier shelves or lugs 51 and transfer them from one of the vertical runs of the carrier chain to the other as this carrier chain passes around the four-tooth sprocket wheel.

By reason of the above described angular displacement of the two lower sprocket wheels 47 and 48 relatively to each other, together with the similar relative angular displacement of the two upper sprocket wheels 49 and 50, the article-carrying shelves or lugs 51 in the front and rear vertical runs respectively of the respective carrier chains A and B will occupy intermediate levels midway between each other, and these shelves or lugs 51 will have similar intermediate angular positions relatively to each other for the respective carrier chains as they pass around their sprockets, as will be clear from Figs. 1, 2, 4, 6 and 10 of the drawings, perhaps more particularly the latter. Thus for each complete rotation of the sprocket wheels, eight articles or packages may be delivered from the bottoms of the runs of the two carrier chains A and B, four deliveries

being made from each carrier chain, and for each one-eighth turn of the sprockets one article or package will be delivered, these deliveries being made alternately by the respective carrier chains

5 A and B.

In the embodiment of the invention shown in the drawings, each of the carrier chains A and B is made up of an even number of links, which in the particular machine illustrated is sixty-two 10 links in each of these chains. By reason of this even number of links, the lower and upper right hand sprockets 47 and 49, and correspondingly the lower and upper left hand sprockets 48 and 50, at all times will have the same angular position 15 relatively to each other, as indicated more particularly in Fig. 2 for the left hand carrier chain B and its sprockets 48 and 50. Also by reason of this even number of links in the chain, taken together with the angularly displaced relation 20 of the right and left hand pairs of sprockets, the projecting outer edges of the carrier shelves 51 in the vertical runs of the respective chains A and B, throughout the length of these runs, will be in staggered relation or offset alternately 25 forward and rearward for the respective chains as the sprocket wheels occupy different rotative positions, as is clearly shown in the drawings for one of these positions (Figs. 2, 4 and 10). However, this is merely harmlessly incidental to the 30 operation and is referred to only as explanatory of what is shown in the drawings.

Packages 57, of which only a few are shown for clarity of the drawings, may rest upon and be supported by the carrier lug shelves 51 of 35 both the front and rear runs of both of the carrier chains A and B. By reason of the free open space provided in the lower part of the casing box at the rear of the coin controlled mechanism, it is desirable in the machine shown to 40 deliver the packages 57 from the lower ends of the rear runs of the carrier chains, rather than from the front runs thereof, by reason of the fact that the space beneath the lower ends of the front runs of these chains is somewhat restricted 45 by the coin controlled mechanism. Therefore, for effecting the delivery of a single package 57 at each operation of the machine, the lower sprockets 47 and 48 are to be rotated a step of a one-eighth turn in a clockwise direction 50 as viewed in Figs. 2 and 10, whereupon a single package 57 will be delivered from one or the other of the carrier chains A or B, and alternately by these chains at the successive operations, comprising a one-eighth turn of all of 55 the sprocket wheels with corresponding concomitant traveling movement of the two carrier chains A and B.

It is desirable of course that a free and unobstructed delivery of each package 57 should 60 be effected straight downward from each of the package-carrying shelves 51 into the open upper end of the above noted delivery chute, and it is similarly desirable that each package 57 should remain in substantially undisturbed position 65 upon its supporting shelf 51 until the moment of its delivery has arrived. For accomplishing this, an inwardly curved downwardly inclined guide plate 58 is provided to extend from the inner side of the casing back 1 at the rear of the lower 70 portions of the descending rear runs of the carrier chains A and B and terminating in a lower delivery edge beneath these rear runs where they pass around beneath the lower sprockets 47 and 48. This guide plate 58 is particularly ad- 75 vantageous in view of the fact that at each

one-eighth delivery turn of the lower sprockets 47 and 48, one of the package-carrying shelves 51 will stop at a position of rest in which it is downwardly inclined towards the rear at an angle of about 45°, so that thereby in this position without the guide plate 58, this package would slide rearward against the rear wall 1 and its delivery at this inclined position would be thus obstructed and uncertain, besides the liability of damage to the package, as will be clear from Fig. 10, for the right hand carrier chain A. It will be clear that at the next movement of this inclined package-carrying shelf 51, shown in Fig. 10, that this shelf will then have a vertical position which is shown in this figure, mostly by dotted lines, for the left hand carrier chain B, so that the package 57 may then drop straight downward into the open upper end of the delivery chute, down which it will slide to the front of the casing, from which it may be conveniently removed by the customer.

It may be further noted that the carrier chains A and B are so placed on their sprockets that the package-carrying lugs or shelves 51 on the rear descending or delivery runs thereof project from 100 the upper ends of the chain links. It will be clear, particularly from Fig. 10, that this arrangement of the carrier chains will result in the dropping of a package 57 for delivery somewhat more towards the rear wall 1 of the casing, 105 the advantage of which has been above noted. In any case it will be obvious that the two chains A and B should be arranged in the same manner, each as the other, on their sprockets, in order thereby to operate alternately in delivering 110 the packages 57.

It will be noted that the packages 57 carried by both the front and the rear runs of the respective carrier chains A and B will be guided at their outer ends laterally by the frame plates 17 and 18, and at their adjacent inner ends will be guided by the intermediate partition wall 21, while at the front the upwardly moving packages 57 will be guided by the guide plate 23 carried by the front door 12, and at the rear of the casing the descending packages 57 will be similarly guided along the inner side of the rear casing wall 1, until finally these descending packages 57 successively reach and ride upon the downwardly inclined guide plate 58, beyond the free lower edge of which they will be delivered one at a time, as above noted. It will now be clear that each of the carrier lugs or shelves 51 may carry thereon a package 57, excepting only the lowermost lugs 120 51 below the lower sprocket wheels 47 and 48. Accordingly, the vending machine shown in the drawings, when both of these carrier chains A and B are fully loaded, will have a total capacity of 122 packages 57.

The driving connections for operating the lower sprocket shaft 27, in carrying out the invention, include a train of movement-reducing gears, which terminate in the above noted operating gear 28, the hexagonal aperture of which fits closely over the right hand end portion of this sprocket shaft 27. This spur operating gear 28 is engaged by a spur idler gear 59 which is located diagonally downward and forward from the operating gear 28 (Figs. 2 and 4). This idler gear 59 is rotatable on a stub shaft 60 which is rigidly secured to and projects inward from the adjacent right hand inner casing wall or frame wall 6, this idler gear 59 being held in place upon its shaft 60 by means of an inner washer 61 and 145 150

an abutment pin 62 through the end of the shaft 60 (Figs. 6 and 7). Forwardly from its lower side the idler gear 59 is engaged by a spur driving gear 63 which is a movement-reducing gear, 5 of one-half the diameter and having accordingly one-half the number of gear teeth of the large operating gear 28. In carrying out the invention, one-quarter turn steps of rotative movement are imparted to this driving gear 63, which 10 therefore communicates one-eighth turn steps of rotative movement to the operating gear 28, such as are required.

This driving gear 63 is loosely rotatably mounted upon a reduced cylindrical end portion 15 of a horizontal transversely extending drive shaft 64, which throughout the major portion of its length is of hexagonal shape, similar in that respect to the two sprocket shafts 27 and 40. At its right hand end, outwardly from the 20 driving gear 63, the extreme end portion of this drive shaft 64 is journaled in a bearing 65 having a flanged head at its outer end and a screw threaded stem passing inwardly through the right hand frame wall 6, a securing nut 66 being 25 screwed over the inner end of this bearing stem, which latter forms an abutment for the driving gear 63. This driving gear 63 at its inner side has a clutch member 67 formed in the same piece therewith. The end of this clutch member 67 at 30 its periphery has four projecting clutch teeth which have abrupt faces circumferentially on both sides thereof, being formed by means of square-faced notches (Figs. 1 and 7). This driving gear 63, together with the clutch member 35 67 formed integrally therewith, is prevented from sliding inward on the cylindrical reduced portion of the drive shaft 64, by means of a washer 68 and an abutment pin 69 passing through the drive shaft 64 just inward from the washer 68.

40 In carrying out the invention, a normally engaged releasable clutch member 70 is provided for engagement with the clutch member 67 of the driving gear 63, for normally positively locking this gear to the drive shaft 64 against relative 45 rotative movement in either direction. This clutch member 70 is of a bell shape or cup shape of the same outer diameter as the clutch member 67, and the open end of this cup clutch member 70 is notched to provide a circumferential series 50 of four substantially rectangular clutch teeth having abrupt faces on both of their sides and being complementary to and fitting snugly but slidably into the above noted notches provided between the clutch teeth of the clutch member 55 67 (Figs. 1 and 7). At its left end this clutch member 70 has a tubular stem or sleeve the axial hole or bore through which is of hexagonal shape, to fit snugly but slidably on the adjacent hexagonal portion of the drive shaft 64, by reason of 60 which this clutch member 70 will be rotatably coupled to the drive shaft 64, while at the same time it will be slidable thereon. When this 65 slideable clutch member 70 is slid towards the right, as shown in the drawings, its clutch teeth will be brought into driving and double locking engagement with the clutch teeth of the clutch member 67 on the driving gear 63, and by sliding this clutch member 70 to the left along the drive shaft 70 64, its clutch teeth will be disengaged from those of the clutch member 67, so that then the driving gear 63 will be uncoupled from the drive shaft 64 for the free rotative movement of this driving gear 63 in either direction.

75 The slideable clutch member 70 is maintained

in driving and locking relation with the clutch member 67 by means of an automatically acting catch or latch device comprising an annular groove 71 in the hexagonal drive shaft 64, and a yieldable latch ball 72 to seat in this groove and 80 contained in the inner end of a radial bore in a thickened portion or boss formed on the clutch sleeve. The latch ball 72 is yieldably pressed into the groove 71 by a small coiled thrust spring 73 which is held under suitable compression by an abutment screw 74 in the outer enlarged end of the said bore. When the clutch member 70 is slid 85 towards the left the ball 72 rides out of the groove 71, and it is only necessary thus manually to slide the clutch member 70 along the drive shaft 64 in order thereby to disengage it from the clutch member 67. When the clutch member 70 is slid back again to its right hand position with its clutch teeth in engagement with those of the clutch member 67, the spring-pressed ball 72 will snap into the groove 71 thereby preventing the possibility of accidental disengagement of the releasable clutch member 70 from its co-operating clutch member 67.

Inasmuch as four, which is the number of the 100 interengaging clutch teeth, is a divisional part of eight, which is the number of rotative steps of movement to be imparted to the operating gear 28, it will be noted that the correct timing between the lower sprocket shaft 27 and the drive 105 shaft 64, will thereby at all times be preserved, when the sliding clutch member 70, after having been disengaged from the clutch member 67, is again reengaged therewith. Also it will be noted that never more than a maximum of a one- 110 eighth turn will be required of the driving gear 63 in order to bring the notches between the clutch teeth of the clutch member 67 into alignment with the clutch teeth of the released clutch member 70, in order thereby to permit the reengagement of the clutch teeth of this releasable clutch member 70 with those of the clutch member 67 on the driving gear 63.

In carrying out the invention, the left hand end of the drive shaft 64 is connected to a manually operable step-by-step operating mechanism, by which this shaft is normally positively locked against rotation in either direction and by which in operation it has quarter turn positively determined steps of rotative movement imparted thereto. These quarter turn movements of the drive shaft 64, together with its stopping and locking against displacement at the end of each such movement, is essential to the correct timing and operation of the package-delivering carrier 120 chains A and B, according to which the two lower sprockets 47 and 48 will be held in their correct normal position and given a one-eighth turn for effecting the delivery of a single package 57, as above described. So far as the above 125 described dispensing mechanism of the present invention is concerned, any suitable step-by-step operating mechanism which is capable of operating the drive shaft 64 in the above noted proper manner may be employed in carrying out the 130 herein claimed invention. For commercial reasons, this invention has been embodied in a coin controlled vending machine, as indicated in the drawings. Since the coin controlled mechanism of my above noted Patent No. 1,734,739 provides 135 a suitable step-by-step operating mechanism for carrying out the present invention, it has been utilized for that purpose, and accordingly the left hand end of the drive shaft 64 has been connected thereto to be operated and controlled through the 140 145 150

intermediary of such coin controlled mechanism, which, in the illustrated embodiment of the invention, constitutes the only means shown by which the dispensing mechanism of this invention can be operated.

By inserting a proper coin through a coin slot 75 provided in the front plate 14 of the coin controlled mechanism and then rotating a front operating handle 76 through about a one-fourth turn in a clockwise direction, the delivery mechanism of this invention will be operated to deliver a single package 57, as above described. When the handle 76 is thus rotated or rocked, following the insertion of a coin, a normally locked spur gear 77 belonging to the coin controlled mechanism will be rotated through a positively determined step of a one-fourth rotative movement, this coin controlled gear 77 being loosely rotatably mounted upon a stud shaft 78 which projects rearwardly from the main frame piece 15 of the coin controlled mechanism. This spur gear 77 engages and operates a similar spur gear 79 of the same diameter and having the same number of gear teeth.

In the carrying out of the present invention, this gear 79 of the coin controlled mechanism is loosely rotatably mounted upon a stud shaft 80. This stud shaft 80 is directly above the stud shaft 78 and projects rearwardly from an auxiliary frame piece 81 which is fixedly secured to the front and upper part of the main frame piece 15 by any suitable means, such as screws (not shown). The upper gear 79 is rotatably held upon its shaft 80 by means of an inner washer 82 and a retaining pin 83 through the inner end of this shaft 80. This upper spur gear 79 at its forward side has a miter gear or bevel pinion 84 formed thereon in one piece therewith. At the right of its axis as viewed from the front (Fig. 6) this bevel pinion 84 engages with and drives another bevel pinion or miter gear 85, these two bevel pinions 84 and 85 being of the same size with the same number of gear teeth on each. On its back at the right this bevel pinion 85 has a rather long cylindrical boss 86 formed in the same piece therewith and this boss is journaled in a bearing 87 formed on the auxiliary frame piece 81 at the top thereof. The axis of this journal boss 86 is in the same horizontal plane with the common axis of the connected gears 79 and 84 (Figs. 6 and 10).

The framework of the coin controlled mechanism is so disposed in the casing that the axis of the journal boss 86 is in axial alignment with the drive shaft 64 of the dispensing mechanism and the left hand end of this hexagonal drive shaft is snugly but removably seated in a hexagonal socket provided in the adjacent end of the journal boss 86 of the bevel pinion 84 (Figs. 6 and 10). It will be noted that the spur gear 77, is the first or initial gear in the train or series of intermeshing gears included in the driving connections for operating the drive shaft 64 and that this gear 77, which is a drive gear, at all times has a positive geared connection with this shaft 64. This initial drive gear 77 is operated under coin control by power transmitted through the coin controlled mechanism from the operating handle 76. At each such operation this normally locked gear 77 will have a quarter turn movement imparted thereto in a counter-clockwise direction as viewed from the front (Fig. 6), this gear 77 being first unlocked then rotated and then again relocked at each operation by

means of the coin controlled step-by-step operating mechanism.

By tracing the connections through the train of gearing, it will be seen that this initial drive gear 77 will transmit positively determined quarter turn steps of rotative movement to the drive shaft 64 of the dispensing mechanism in a clockwise direction as viewed from the right hand side of the machine (Fig. 10). By further following the driving connections from the drive shaft 64, through the engaged clutch members 70 and 67 and train of gears 63, 59 and 28 to the lower sprocket shaft 27, it will be seen that the lower sprocket shaft 27 is normally positively locked against movement in either direction and that a one-eighth turn step of rotative movement in a clockwise direction as viewed from the right hand side of the machine (Figs. 2 and 10) will be transmitted to this sprocket shaft 27 at each coin controlled operation of the operating handle 76, whereby a single package 57 will be delivered downward from the descending rear run of one of the carrier chains A or B, and alternately by these chains at successive operations of the machine.

In carrying out the invention a visual indicator is provided for showing upon inspection when the magazine of the machine requires replenishing with articles to be dispensed, that is, when the carrier chains A and B need to be refilled with packages 57 to be delivered thereby. An indicating device includes an operating lever shown as formed of a single suitably bent rod. An intermediate horizontal shaft portion 88 of this bent lever is pivoted in a long bearing formed by a bracket clip 89 secured to the inner side of the left hand inner casing frame wall 7 at a suitable distance below the bearing 25 for the left hand end of the lower sprocket shaft 27. The bearing formed by this clip 89 is shown (Fig. 10) as extending rearwardly from about in line with the pivot pins 56 in the front vertical run of the left hand carrier chain B to about in line with the middle of the length of the package-carrying lug shelves 51 on the rear vertical run of this left hand carrier chain B.

This shaft 88, at the rear of its bearing 89, has an upstanding lever arm comprising a lower straight portion 90, an inwardly bent short shoulder-forming portion 91, and a straight upright feeler portion 92 parallel with the lower arm portion 90, the upper end of this feeler portion 92 being bent outward at an upward inclination to form an inclined upper end portion 93. At the front end of its bearing 89 the shaft 88 is provided with a crank arm 94 which extends inwardly at substantially a right angle to the shaft 88 and at a slightly acute angle to the lower portion 90 of the upright lever arm. The crank arm 94 terminates in a rather long horizontal crank stem end portion 95 which projects forward in parallel relation with the shaft 88. The forward end of this crank portion 95 of the bent lever projects beyond the front of an indicator plate 96 through a vertical slot 97 therein. This indicator plate 96 is spaced rearwardly from the left hand portion of the front door 12 of the casing in parallel relation therewith and the left end of this indicator plate 96 has a rear flange by which it is secured to the inner side of the adjacent left hand inner frame wall 7 of the casing (Fig. 10).

At the front of the indicator plate 96 the projecting end of the crank stem 95 engages in the slotted end of an indicating arrow 98 which, in-

termidate of its length, may rock on a pivot stud 99 which projects from the front of the indicator plate 96, this pivot stud 99 being located at the right of the vertical slot 97 with the arrow 98 pointing towards the right as viewed from the front of the machine (Figs. 1 and 6). Near its right end the indicator plate 96 is provided on its front face with the upper and lower legends "Empty" and "Full" between and adjacent to which two radial indicating marks are also provided outwardly from the ends of the arrow 98. The arrow 98 and the legend-carrying portion of the indicator plate 96 are visible through a transparent plate 100 providing a window in the door 12, this window plate 100, which may be of glass, being supported on the door 12 by means of a frame 101 (Fig. 10).

A two-armed wire spring 102 has a middle coil which is held by a headed anchor stud 103 which projects rearwardly from the back of the indicator plate 96 at a point intermediate between its vertical slot 97 and its above noted securing flange at the left end thereof. The end of one of the arms of this spring 102 bears against the inner side of this flange of the indicator plate 96 while the other arm of this spring has its end turned downwardly and engages over the top of the crank stem 95 just at the back of the indicator plate 96 (Figs. 6 and 10). The rear edge margin of the lower end portion of the left hand carrier frame plate 18 is cut away to form a long vertical notch 104 (Fig. 2) which provides for the free inward rocking movement of the feeler arm, the lower straight portion 90 of which normally extends vertically adjacent to the inner side of the frame wall 7 while the straight feeler portion 92 extends vertically just at the inner side of the carrier frame plate 18 with the upper inclined end portion 93 projecting to the outer or left hand side of this carrier plate 18 (Fig. 6).

It will be noted that the spring 102, acting upon the crank stem 95, has a tendency to swing the feeler 92 inward towards the right away from the left hand carrier frame plate 18. Normally this feeler 92 is engaged by and abuts against the adjacent ends of the lowermost horizontal package 57 which is carried by the rear run of the left hand carrier chain B and this feeler 92 is shown as of a length for similarly abutting against about the last three packages 57 on this vertical run (Figs. 1, 2, 6 and 10). This normal upright position of the feeler 92 holds the crank stem 95 at the upper end of the slot 97 in the indicator plate 96 with the barbed end or head of the arrow 98 pointing to the indication "Full" (Figs. 1 and 6). When the last package 57 carried by this rear vertical run of the left hand carrier chain B is moved downward around the lower left hand sprocket 48 from the horizontal position of this package (Fig. 2) to the inclined position thereof in engagement at its outer edge with the downwardly and inwardly inclined guide plate 58, this lowermost package will then pass below the feeler 92 and its lower shoulder 91, so that the feeler 92 will then be free to be moved inward by the spring 102.

For example, Fig. 2 shows a single package 57 at its lowermost horizontal position on the rear run of the left hand carrier chain B. At the next operation of the machine as there shown, this package 57 will be moved to the above noted lower inclined position in which it will release the feeler 92, and it may be noted that this latter position of the package 57 shown in Fig. 2 will then be the same as that shown for the inclined low-

ermost package 57 for the right hand carrier chain A in Fig. 10. It will thus be evident, in the construction shown, that with both of the carrier chains A and B fully loaded with packages 57, one of these packages, which will be the last package carried by the left hand carrier chain B, will always be left in the machine preparatory to its replenishing with a fresh stock of the packages. When the spring 102 thus moves the feeler 92 inward when it is no longer restrained by a package 57, it will concomitantly move the crank stem 95 down to the lower end of the slot 97 in the indicator plate 96 and at the same time will rock the arrow 98 in a counter-clockwise direction (Figs. 1 and 6), to a position in which it will then point to the legend "Empty", thereby giving the visual indication that the stock of packages 57 requires replenishing.

This above described visual indicating device is in general similar to that disclosed but not claimed in my above noted Patent No. 1,734,739. Also, together with this indicating feature of the dispensing mechanism of this invention, there is shown in the drawings a slot closing device for closing or obstructing the coin slot 75 against the insertion and consequent loss of a coin in the machine when the magazine is empty. This slot closing device relates to the coin controlled mechanism and is shown as substantially similar to that disclosed in my last above mentioned patent.

This slot closing device includes a horizontal rock shaft 105 pivoted in a bearing 106 on the rear of the main frame plate 15 of the coin controlled mechanism. At the left end of this bearing this rock shaft 105 has a forwardly extending crank arm 107 which terminates adjacent to the inner side of the left hand carrier frame plate 18 in a horizontal crank pin 108. This crank pin 108 is pivotally connected by means of a laterally bent link 109 with the crank stem 95 of the indicating device to be operated thereby, which thus performs a double function, one of which relates to the dispensing mechanism and the other of which relates to the coin controlled mechanism. This slot closing device may be disregarded so far as the present invention is concerned.

As examples of slot closing devices alone, reference may be had to my above noted Patent #1,722,230 and also to my Patent No. 1,728,901, dated September 17, 1929, for Vending machine, while for an example of a slot closing device and an indicating device employed in the same vending machine independently of each other, reference may be had to my Patent No. 1,751,246, dated March 18, 1930, for Coin controlled mechanism, taken in connection with its divisional Patent No. 1,738,721, dated December 10, 1929, for Web dispensing device. It is obvious that the above noted slot closing device which is disclosed incidently in the drawings may be omitted in carrying out the present claimed invention.

The carrier chains A and B may of course be refilled at any time desired with a renewed stock of packages 57 to be dispensed. However, in case this has not been done, the movable arrow 98 of the visual indicator will finally direct attention to this need. When the stock of packages 57 is to be renewed, the front door 12 is opened or removed, carrying with it the top cover 13. The sliding clutch member 70 may now be conveniently shifted to the left along the driving shaft 64 for disengaging its clutch teeth from those of the cooperating clutch member 67, thereby setting free the drive gear 63 for independent rotative movement in either direction. Both of

the carrier chains A and B could now be completely refilled from the front of the machine by turning these chains over in the direction of their normal travel as the filling from the front 5 proceeds. However, the invention provides a quicker and more convenient way for fully re-loading these carrier chains.

The two pivoted gravity latches 34 are lifted out of engagement with the studs 35 on the carrier frame and the latter is let down to its forwardly projecting inclined position shown in Fig. 4, in which the carrier frame will then be supported by the folding side links 36. The rear runs of these carrier chains A and B may then 10 be completely refilled from above at the front of the casing box. No particular order needs to be followed in doing this other than to be careful that all of the successive spaces between the carrier lugs or shelves 51 are filled, each with 15 a package 57. As a further convenience, the carrier chains A and B may be freely moved in either direction at any time. It has been found convenient to begin the filling of these chains towards the bottoms or lower ends of their runs 20 and move the rear runs of these chains downward as the filling proceeds. When the filling of the rear runs of the carrier chains has been completed, the chain-carrying carrier frame is rocked back to its normal upright position, in 25 which it will be held by the automatic engagement of the gravity latches 34 with the studs 35. The vertical front runs of these carrier chains A and B may now be conveniently completely 30 filled with the packages 57, care being again exercised, of course, that no intermediate blank spaces are left between the successive shelves 51.

While desirable, it is unessential to the operation that the front runs of these carrier chains should be filled completely down to their lower 40 ends at the bottom. For completely filling these two carrier chains A and B to their maximum capacity, the lowermost packages 57 carried by their rear runs should be as is shown at the right hand side in Fig. 10, while the lowermost packages 45 in their front runs should rest respectively upon the two lowermost horizontal shelves 51 which, for clarity of illustration, are shown as empty at the left side in Fig. 10.

After the rear and front runs of the carrier chains A and B have been thus refilled, and also 50 more desirably and conveniently after the carrier frame has been returned to its normal upright position, the released sliding clutch member 70 may be moved back to its normal operating position in which it will be held by the seating of its latch ball 72 in the groove 71, with the clutch teeth of the two clutch members 67 and 70 in full engagement, for the step-by-step operation 55 of the carrier chains A and B from the drive shaft 64 and their locking against movement relatively thereto and therewith. The front door 12 may now be replaced in its closed condition and the machine is ready for normal operation for the 60 delivery of single packages 57 alternately from the respective carrier chains A and B at each such operation.

It is obvious that various modifications may be 65 made in the construction shown in the drawings and above particularly described, within the principle and scope of the invention as defined in the appended claims.

I claim:

1. In an article dispenser, the combination of 70 an endless traveling delivery chain supported and guided to have front and rear vertical

parallel runs, a sprocket wheel for the delivery chain at the lower end of its runs, a transverse sprocket shaft on which the sprocket wheel is fixed, a casing having a front door to be opened and transversely in which the said sprocket 80 shaft is journaled, and a normally vertical carrier frame carrying the said delivery chain and pivoted at its lower end on the said sprocket shaft to swing forward and downward to the outside of the casing through the open front of the casing to a position in which the rear run of the delivery chain will be freely accessible to be directly loaded from above with articles to be dispensed.

2. In an article dispenser, the combination of an endless traveling delivery chain supported and guided to have front and rear vertical parallel runs, a sprocket wheel for the delivery chain at the lower ends of its runs, a transverse sprocket 85 shaft on which the sprocket wheel is fixed, a transverse drive shaft in spaced parallel relation to the sprocket shaft, step-by-step operating mechanism connected to the said drive shaft for rotating the latter step-by-step, gearing connecting the drive shaft to the sprocket shaft for imparting step-by-step rotative movement to the latter in correctly timed relation, the said gearing including a gear loosely rotatably but non-slidably mounted on the said drive shaft and provided on its inner end with projecting clutch teeth which are abrupt on both sides thereby to form a positively acting clutch member, and a second clutch member rotatable with but 90 slidable along the drive shaft provided on its end adjacent to said gear with clutch teeth complementary to those on the said gear for positively acting engagement therewith and to be disengaged therefrom by sliding the said 95 slideable second clutch member away from the gear 100 so that then the said delivery chain may be freely moved in loading it with articles to be dispensed, the said interengaging clutch teeth on the clutch members being disposed in such manner that when the slideable clutch member 105 is reengaged with the clutch member on the said gear the correctly timed driving relation of the drive shaft with the sprocket shaft will be 110 preserved.

3. In an article dispenser, the combination 115 of a pair of similar endless traveling delivery chains supported and guided for each chain to have front and rear vertical parallel runs substantially in lateral alignment with the same runs of the other chain, equally spaced outwardly projecting carrier lugs on each of the chains, a positive connection between the two chains to compel their concomitant traveling movement so that thereby the two chains will 120 deliver articles in timed relation relatively to 125 each other in the dispensing operation, a casing having a front door to be opened, and a normally vertical carrier frame carrying the said delivery chains and pivoted at its lower end in the casing to swing forward and downward to 130 the outside of the casing through the open front of the casing to a position in which the rear runs of the delivery chains will be freely accessible to be directly loaded from above with articles to be dispensed, the said pivoted carrier 135 frame including vertical side walls, a vertical transverse partition wall at right angles to the side walls between the front and rear vertical runs of both of the said delivery chains, and a vertical intermediate partition wall parallel with 140

the said side walls between the two delivery chains, these vertical walls forming four rectangularly arranged article-guiding channels which are open at the front and rear of the pivoted carrier frame, a rear vertical guide for articles on the rear runs of the delivery chains being provided by the rear wall of the casing and a front guide for articles on the front runs of the delivery chains being provided by the front door.

4. In an article dispenser, the combination of a pair of similar endless traveling delivery chains supported and guided for each chain to have front and rear vertical parallel runs substantially in lateral alignment with the same runs of the other chain, equally spaced outwardly projecting carrier lugs on each of the chains, a positive connection between the two chains to compel their concomitant traveling movement so that thereby the two chains will deliver articles in timed relation relatively to each other in the dispensing operation, a casing having a front door to be opened, and a normally vertical carrier frame carrying the said delivery chains and pivoted at its lower end in the casing to swing forward and downward to the outside of the casing through the open front of the casing to a position in which the rear runs of the delivery chains will be freely accessible to be directly loaded from above with articles to be dispensed, the said pivoted carrier frame including vertical side walls, and a vertical intermediate partition wall parallel with the said side walls between the two delivery chains, these vertical walls forming article-guides which are open at

the front and rear of the pivoted carrier frame, a rear vertical guide for articles on the rear runs of the delivery chains being provided by the rear wall of the casing and a front guide for articles on the front runs of the delivery chains being provided by the front door.

5. In an article dispenser, the combination of an endless traveling delivery chain supported and guided to have front and rear vertical parallel runs, a sprocket wheel for the delivery chain at the lower end of its runs, a transverse sprocket shaft on which the sprocket wheel is fixed, an enclosing casing including vertical side walls and having a front door to be opened and transversely in which the said sprocket shaft is journaled, a normally vertical carrier frame carrying the said delivery chain and having vertical side walls pivoted at their lower ends on the said sprocket shaft to swing forward and downward to the outside of the casing through the open front of the casing to a position in which the rear run of the delivery chain will be readily accessible to be directly loaded from above with articles to be dispensed, means for supporting the carrier frame at its forwardly swung loading position connecting a side wall of this carrier frame to the adjacent side wall of the casing and positioned so as to leave the rear run of the carrier chain unobstructed for loading, and an automatically-engaging positively-holding releasable latch for normally positively holding the carrier frame in its vertical dispensing position in the casing.
